SOOT BLOWER FOR DOUBLE WALLED
BOILER SETTINGSDe Los E. Hibner and Fred C. Arey, Du Bois, Pa.,
assignors to Vulcan Soot Blower Corporation,
a corporation of Pennsylvania

Application October 9, 1942, Serial No. 461,408

3 Claims. (Cl. 122—392)

The present invention relates to soot blower means, particularly as applied to installations in which the boiler setting is provided with double walls spaced apart from each other; and has for its object to make it possible to cause all of the blower apparatus except a few simple actuating parts, to be concealed within the place between the sections of the double wall on which the units are mounted.

When the heads of the blower units are located between the two sections of the double wall, the outer wall section may be removed without disturbing the blower installation, provided that the external actuating means does not interfere. A further object of the present invention is so to construct and arrange the actuating mechanism that it can easily be applied to or be removed from the blower apparatus at will; thereby simplifying the work of installing the system and of removing the outer wall section. The various features of novelty whereby our invention is characterized will herein-after be pointed out with particularity in the claims; but, for a full understanding of our invention and of its objects and advantages, reference may be had to the following detailed description taken in connection with the accompanying drawings, wherein:

Figure 1 is a vertical section showing a fragment of a boiler including a double wall, together with a series of three blower units, embodying the present invention, arranged one upon the other; Fig. 2 is a vertical section on a larger scale than Fig. 1, showing only the lower blower unit, in section; Fig. 3 is a section on a somewhat larger scale than Fig. 1 on line 3—3 of Fig. 1; Fig. 4 is a section on line 4—4 of Fig. 2, only the extension of the rotatable blower element and the part of the actuator surrounded thereby being shown; Fig. 5 is an elevational view, on a smaller scale than Fig. 1, looking at the boiler from the outside, lengthwise of the blower element and illustrating an actuating means common to all of the units; and Fig. 6 is a side view of the actuating means appearing in Fig. 5.

Referring to Fig. 1 of the drawings, A represents the inner section and B the outer section of a double wall for a boiler setting in which are contained tubes C. In the particular arrangement shown, three tubular, rotatable, jetting or blower elements are required to keep clean the particular tubes appearing adjacent to the wall that is shown. Each of these tubes forms part of a blower unit which may be a

conventional type; and all three may be alike. Each unit includes a head 4 adapted to be supplied with steam or other cleaning fluid through an inlet pipe 5; the corresponding tubular blower element extending at one end into and being rotatable in the head. It will be seen that the heads 4 are mounted on the inner wall section with the space between the two sections and independently of the outer section.

10 Details of the blower units and their actuators, as well as of their mountings, are shown more fully in Figs. 2-4 in which one of the complete units and its actuator is illustrated. It will be seen from Fig. 2 that the jetting or blower element 3 is provided with a tubular extension 6 that passes entirely through and is rotatable in the head 4 secured in any available way to the outer side of the inner wall section. The members 3 and 6 are connected together by a suitable coupling sleeve 7 which serves also as a shoulder to prevent the extension from being drawn outwardly through the head. Surrounding the extension, just beyond the outer side of the head, is a detachable collar 8. Therefore the extension is held against lengthwise movement relatively to the head by the sleeve 7 and the collar 8, until the collar is removed. The member 6 contains an imperforate partition 9 extending across the interior thereof toward its outer end. A short distance inwardly from the partition 9 are the usual ports 10 which permit steam or other cleaning fluid to pass from the head into the member 6. Within the head, and surrounding the member 6 toward 25 the free end of the latter, is a suitable packing 11 to prevent steam escaping in the outward direction past the member 6 from the interior of the head.

20 The actuator for turning the blower element 3 is shown as comprising a shaft 12 that is aligned with the blower element and extends through a stuffing box 14 and in the outer well section B. The member 6 and 12 are provided with suitable interlocking parts that are engaged with each other upon moving the member 12 inwardly, and which constitute a driving connection by means of which the actuator and the blower element rotate in unison when the actuator is turned. In the arrangement shown, the outer end of the member 6 contains a square hole 15 while the shaft 12 has a squared end 16 that fits loosely into this hole. This part 16 of the actuator is shown as having in one side a deep longitudinal groove 17 into which extends a pin 18 fixed in 30 the wall of the member 6. The pin and groove 35

connection insures that the actuating shaft will always be in the same angular position relatively to the blower element when coupled thereto.

The shaft 12 extends for some distance outwardly from the stuffing box 14 and is supported at its outer end in a bearing in an upright plate or bar 19 which is in turn supported from studs 20 extending outwardly from a pair of oppositely projecting vertical arms 21 on the stuffing box.

On the shaft 12, in the space between the arms 21 of the plate 19, are one or more sprocket wheels. In the arrangement shown in Fig. 2 there are two of these wheels, 23 and 24, locked to the shaft by means of a strong key 22 against rotation relatively thereto. The sprocket wheel 23 is provided with a lateral projection 25 that is adapted to strike against lugs 26 and 27 on the plate 19 at the limits of the angle through which the blower element must be moved. Either of the two sprocket wheels may constitute the driven wheel while the other serves as a driver for the next higher unit.

It will be seen that the actuating shaft or the entire actuator can be detached without in any way disturbing the blower unit proper. So also, the wall B can be taken down and rebuilt with the assurance that the blower element remains properly disposed with respect to the boiler tubes with which it is associated.

When there are several blower units in what may be termed a battery, as shown, each unit may be operated in any way best suited for the particular boiler with which the devices are associated. In the arrangement shown, means are provided for operating all three blower elements in unison with each other. Thus, as shown in Fig. 1, the actuator for the middle unit has sprocket wheels, 28 and 29, directly above the wheels 23 and 24, respectively; while the actuator for the upper unit has a single sprocket wheel 30 directly above and in the plane of the wheels 24 and 29. The wheel 24 may be driven in any suitable way, while, by means of suitable sprocket chains, the wheel 23 drives the wheel 28 and the wheel 29 drives the wheel 30. If the wheels are all alike, the three blower elements will turn in unison through equal angles when the lower element 3 is turned, the maximum angle through which any element can be turned being determined by the lugs 26 and 27 and the projection 25.

In Figs. 5 and 6 is shown a simple means for operating all of the units, in unison with the other, through the turning of a single handle. There an endless sprocket chain 31 connects together the sprocket wheels 23 and 28, while another endless chain runs around the wheels 29 and 30. The sprocket wheel 24 is driven by an endless chain 34 that passes around a small hand operated wheel 35. The wheel 35 is the output end of a force-multiplying, speed-reducing gearing in a suitable gear case 36; the driving force being delivered at the input side to a shaft 37, protruding from the casing, by a handle or crank 38. The casing 36 may be mounted on any suitable support, such as D, at any point from which it is convenient to run a sprocket chain to the wheel 24.

It will thus be seen that we have produced a simple and novel soot blower system in which no parts of the soot blowers, proper, lie on the exterior of a double walled boiler setting, improving the appearance of the power plant and making it easier to keep the outer wall surfaces clean; that where the furnace is operating under

forced draft, the openings in the walls to permit operation of the blower elements from the outside are sealed to prevent escape of combustion gases into the boiler room; that permits repairs to be made with a minimum amount of disturbance of the soot blower system; and that permits the entire outer wall or casing, of a double wall construction to be removed without disturbing the soot blower units.

10 While we have illustrated and described with particularity only a single preferred form of our invention, we do not desire to be limited to the exact details disclosed; but intend to cover all forms and arrangements coming within the definitions of our invention constituting the appended claims.

We claim:

1. The combination with a boiler setting having a double wall in which the two sections are spaced apart from each other, of a soot blower unit comprising a head mounted in the space between said wall sections and a movable tubular blowing element extending from said head through the inner section, said element extending through said head to the outer side thereof, an actuator for said element extending through the outer wall section into the vicinity of the outer end of said element, cooperating clutch elements on the meeting ends of the element and the said actuator part adapted to be engaged with and disengaged from each other by lengthwise movements of the actuator, and means detachably mounted on the outer wall section and rotatably supporting said shaft while holding it against lengthwise movement.

2. The combination with a boiler setting having a double wall in which the two sections are spaced apart from each other, of a soot blower unit comprising a head mounted in the space between said wall sections and a movable tubular blowing element extending from said head through the inner section, said element extending through said head to the outer side thereof, a stuffing box in the outer section coaxial with said element, an actuating shaft extending from the exterior of said wall through said stuffing box, cooperating clutch devices on said shaft and said element that are engaged with each other through a lengthwise movement of the shaft, and detachable elements on the shaft and stuffing box normally holding the shaft against lengthwise movement relative to the stuffing box while leaving the shaft free to rotate.

3. The combination with a boiler setting having a double wall in which the two sections are being spaced apart from each other, of a soot blower unit comprising a head mounted on the inner wall section in the space between said wall sections and a movable tubular blowing element extending from said head through the inner section, said element extending through said head to the outer side thereof, a transverse partition in said element at some distance inwardly from the outer end, an actuating shaft passing through the outer wall section in alignment with and extending into the outer end of said element, the cooperating ends of the element and the shaft being shaped to be engaged with and disengaged from each other by lengthwise movements of the shaft and to lock the element and the shaft together against relative rotary movements while engaged with each other.
